CLAIM

The ornamental design for a bangle for mobile device, as shown and described.

DESCRIPTION

FIG. 1 is a front view of the bangle for mobile device, showing my new design, the rear view being a mirror image thereof;

FIG. 2 is a left side view thereof, the right side being a mirror image thereof;

FIG. 3 is a top view thereof;

FIG. 4 is a bottom view thereof;

FIG. 5 is a cross sectional view thereof, taken along line 5-5 shown in FIG. 3;

FIG. 6 is a cross sectional view thereof, taken along 6-6 shown in FIG. 3; and,

FIG. 7 is a perspective view thereof, shown in a state of use. The broken lines in the drawings represent portions of the bangle for mobile device and form no part of the claimed design. The other dot-dash lines in FIG. 3 represent cross sectional view indicia and form no part of the claimed design.

The dot-dash lines in FIGS. 1 through 3 and 5 through 7 represent a boundary and form no part of the claimed design.
